UNITED STATES PATENT OFFICE.

ISAAC R. BURKHOLDER, OF LANCASTER, PENNSYLVANIA.

GATE.

1,316,080.

Specification of Letters Patent. Patented Sept. 16, 1919.

Application filed January 11, 1919. Serial No. 270,767.

To all whom it may concern:

Be it known that I, ISAAC R. BURKHOLDER, a citizen of the United States, and a resident of Lancaster, in the county of 5 Lancaster and State of Pennsylvania, have made certain new and useful Improvements in Gates, of which the following is a specification.

My present invention relates particularly 10 to pull gates which may be opened and closed from either side and at points distant from the gate setting proper, flexible connections leading to the gate operating means from such distant points, and the 15 primary object of my invention is to provide certain improvements in connection with the generally well known gate of this character for the purpose of promoting better and more effective operation, as well 20 as simplifying the action of the gate and the structure of its operating parts.

In the accompanying drawings which illustrate the present invention:

Figure 1 is an elevation of the gate in 25 closed position;

Fig. 2 is an enlarged detail partly in elevation and partly in section of a portion of the gate and its operating means;

Fig. 3 is a plan view of the gate and its 30 operating means;

Fig. 4 is an enlarged horizontal section taken substantially on line 4-4 of Fig. 1, and,

Fig. 5 is a similar view taken substantially on line 5-5 of Fig. 2.

Referring now to these figures, the gate as proposed by my invention is in the nature of a rectangular frame 10 which may be made of any suitable material with any 40 suitable mesh body 11, which may be more or less close and of more or less strength, depending upon the use and requirements. The gate closes between uprights or posts 12 and 13, 12 being the hinge post and 13 45 being the catch post, the latter having a bifurcated catch plate 14 with which the lower free end of a spring catch arm 15 cooperates. This catch arm 15 extends through a guide piece 16, and with the 50 guide piece is secured to the side of the gate opposite to that which carries the upper and lower hinge clamps 17 and 18.

The relative disposition of the above mentioned parts is most clearly to be seen by 55 reference to Fig. 1, wherein it will be noted that the lower portion of the hinge post 12

has a laterally projecting arm 19 provided with an upwardly projecting stud 20 extending through a bearing opening in the lower hinge clamp 18, the latter of which 60 and the upper clamp 17 having portions at their inner ends, as seen at 21 in Fig. 5, which embrace the adjacent side of the gate frame 10 and are securely clamped thereto by clamping screws 22.

The upper portion of the hinge post 12 has vertically spaced apertured laterally projecting bearing members 23 and 24 in which an operating upright 25 is rotatably mounted, this upright being provided with 70 a laterally projecting arm 26 intermediate its ends having a slotted opening 27, as best seen in Figs. 2 and 5, within which the depending pin 28 of the upper hinge clamp 17 of the gate frame is both rotatable and 75 slidable.

By reference again to Fig. 1 it will be noted that the lower hinge clamp 18 is of considerably greater length than the upper hinge clamp 17, so as to bring the upright 25 into vertical alinement with the pintle of the lower hinge of the gate. The upright 25 is furthermore provided, immediately above its laterally projecting arm 26, with a pair of spaced juxtaposed ears 80 29, adapted to receive the reduced extension 30 projecting from the free end of the upper hinge clamp 17, for a purpose which will be presently described.

The upper end of the upright 25 projects 90 above the hinge post 12, and upon its upper extremity is secured an arcuate operating arm including a curved rim 31, spokes 32 and a hub 33, the latter provided with a squared opening 34, seated upon the 95 conformably shaped upper portion of the upright 25 and secured by a nut 35. The rim 31 is channeled to receive the inner ends of the oppositely extending operating ropes or connections 36 and 37, which project to 100 latch posts 38 and 39, as seen in Fig. 3, each of which posts has a latch piece 40 to engage the latch arm 15 of the gate when the latter is swung to the fully opened position.

The rim 31 of the operating arm is also 105 provided with openings adjacent its opposite ends and the adjacent end portions of the operating connections 36 and 37 overlap one another within the channel, each being secured at its extremity at 41 through 110 one of the openings of the said rim, the latter having a series of side slots 42 which

both lighten its weight and add to its appearance.

Below the operating arm just above described, the upright 25 has a gate lifting arm 42, one end of which is bifurcated to embrace a portion of the said upright, and is secured thereto by a clamping screw 43 and the opposite or free end of which has an eye 44 to receive one end of the gate connection 45, preferably provided with an interposed coiled spring 46, all as seen in Fig. 1, the opposite end of the gate connection 45 being secured through an eye 47 mounted upon the upper bar of the gate frame 10, so that when the outer end of either of the gate operating connections 36 and 37 is pulled by grasping the respective handle 48, as seen in Fig. 3 in approaching the gate setting proper, from either direction, the upright 25 is rotated and the gate is lifted by virtue of the swinging movement of arm 42, and the pull of the gate lifting connection 45 until the latch arm 15 is shifted free of the latch plate 14, at which time the gate swings both by gravity and through the tension of spring 46 until its latch arm 15 engages the latch piece 40 of one of the latch posts 38 and 39, opposite that upon which pull has first been exerted. After passing through the gate the same operation is repeated by pull upon the free end of the other of the gate operating connections 36 and 37, which lifts the gate from its latched open position and throws the same to closed position, as seen in Fig. 1.

It is thus obvious that for the proper operation of the gate it is essential that its first movement be a lifting movement, in order to free the latch arm 15 and under ordinary circumstances if the gate is permitted to freely swing after such lifting movement, it is obvious that small animals such as pigs, might readily open the gate. To defeat this the upright 25 has the ears 29 before mentioned between which to receive the extension 30 of the upper hinge clamp 17, should the gate frame be raised before the upright 25 is turned, so that being thus engaged with the upright the gate will be locked against swinging movement.

It is obvious from the foregoing that my invention provides a highly effective, efficient gate of the present type, which is simple in its construction, provides against accidental opening or opening by small animals capable of lifting the free end of the gate, and a lasting and durable construction which permits of ready repair and substitution of parts.

I claim:

1. In a swinging gate, the combination of a hinge post and a latch post, the latter of which has a latch piece, a gate frame provided at one side with a latch arm to cooperate with said latch piece, upper and lower hinge clamps secured to the opposite

side of the gate, a rotatable upright journaled upon the upper portion of the hinge post, having a laterally projecting slotted arm intermediate its ends, the upper hinge plate being provided with a pin depending into the said slot of the arm and movable therein, an arm secured to the lower portion of the hinge post and having an upright stud, the lower hinge clamp being greater in length than the upper hinge clamp, and having a bearing engaging the stud in the plane of the axis of said upright, a gate lifting arm carried by the upright and having connection with the upper portion of the gate frame, an operating arm secured to said upright, and flexible connections leading to and secured upon the said operating arm for the purpose described.

2. In a swinging gate, the combination of a hinge post and a latch post, the latter of which has a latch piece, a gate frame provided at one side with a latch arm to cooperate with said latch piece, upper and lower hinge clamps secured to the opposite side of the gate, a rotatable upright journaled upon the upper portion of the hinge post, having a laterally projecting slotted arm intermediate its ends, the upper hinge plate being provided with a pin depending into the said slot of the arm and movable therein, an arm secured to the lower portion of the hinge post and having an upright stud, the lower hinge clamp being greater in length than the upper hinge clamp, and having a bearing engaging the stud in the plane of the axis of said upright, a gate lifting arm carried by the upright and having connection with the upper portion of the gate frame, an operating arm secured to said upright, flexible connections leading to and secured upon the said operating arm, the said upright having spaced ears projecting above its said slotted arm and the upper hinge clamp of the gate frame having a reduced extension movable into the space between the said ears, for the purpose described.

3. The combination with a gate, of a mounting therefor including a lower rigid hinge stud, and an upper rotatable upright alined above the hinge stud and provided with a laterally projecting arm, upper and lower hinge members clamped to the adjacent side of the gate, the lower one of which is extended beyond the upper one and has a bearing engaging the lower rigid stud, the upper hinge plate having a shiftable pivot in connection with the said arm of the upright, a gate lifting arm secured to the upright, and having an elastic connection with the upper portion of the gate frame, and means for rotating the upright, as described.

4. The combination with a gate, of a mounting therefor including a lower rigid hinge stud, and an upper rotatable upright alined above the hinge stud and provided

with a laterally projecting arm, upper and lower hinge members clamped to the adjacent side of the gate, the lower one of which is extended beyond the upper one and has a bearing engaging the lower rigid stud, the upper hinge plate having a shiftable pivot in connection with the said arm of the upright, a gate lifting arm secured to the upright, and having an elastic connection with the

upper portion of the gate frame, means for 10 rotating the upright, said upright having spaced ears above its said arm and the said upper hinge clamp having a reduced extension movable between the ears of the upright when the gate frame is lifted independent of 15 movement of the upright.

ISAAC R. BURKHOLDER.
